GARAGE TOOL

Buford L. Knowles, Haines City, Fla.

Application July 15, 1955, Serial No. 522,309

5 Claims. (Cl. 214—1)

This invention relates to garage tools and has for its principal object the provision of a tool that can readily be mounted on any ordinary floor jack and will support transmissions, differential carriers, etc. so that these mechanisms may be removed from an automobile or truck, repaired, and then secured back in place in the vehicle. An important object of the present invention is to provide a tool of this type which will have general use and may be safely and efficiently used by one man.

A further object of the invention is to provide a base plate to be assembled on a hydraulic floor jack and having on the base plate a pair of spaced rods mounted to form a cradle which can be locked in chosen position, the base also carrying an extensible brace and an adjustable chuck to insure that a heavy truck part will be safe from slipping.

A still further object of the invention is to provide one or more cables secured to spools which are slidably and rotatably mounted one at each side of a base plate, the free end of each cable having a loop which can be secured either to a nut, bolt or other projection on the mechanism being carried or which can be hooked by an anchoring member at the opposite side of the supporting plate.

In the drawings:

Figure 1 is a side view.

Figure 2 is a plan view.

Figure 3 is a bottom plan view, and

Figure 4 is a detail.

In general, the base of my tool consists of a heavy steel plate 10, a convenient size being 10" x 12", which will take care of practically any differential or transmission. On this base plate is mounted a cradle 11, a chuck 12 and a brace 14. At each side the base plate 10 carries a non-circular rod 15 each having an end extension 17 by which the shaft may be rotated by means of a small wrench, the shaft carrying a ratchet wheel 18. By having the rod 15 square in cross-section, it may readily be rotated by an open end wrench applied anywhere along its length, the wrench opening being the same size as the side of the rod or shaft 15. On each of the shafts 15 I mount a non-rotating spool 20 on which is wound a cable 21, one end of which is fastened to the spool and the other end is formed into a loop 22 which may be received by an anchoring piece 23 loose on the opposite shaft 15.

The chuck 12 is a simple strap 25 having upturned ends 26 and 27 which may or may not be of the same height. The strap 25 has a central slot 27 of materially shorter length than the corresponding slot 28 in the base plate 10. Two small guiding lugs 31 and 32 overlie the front edge of the base plate and allow the chuck to slide the entire width of the plate. By spacing the upturned ends 26 and 27 about 5" apart I find that I can take care of differential carriers of almost any car or truck.

The brace 14 is mounted on a round rod 30, pivotally and removably mounted in lugs 34 and 35 extending from the base plate 10. The brace is extensible to a desired length as it is in three telescoping sections 36, 37

2

and 38 which can be secured in adjusted position at the correct length by two thumbscrews 39. The sections of the brace are each channel-shaped in cross section, but the end section 38 is flared to the full width of the metal strip and has a smooth recess 40 so as conveniently to receive, for example, the small end of a differential carrier assembly when the large diameter of this assembly is supported by the chuck at the other end. The brace 14 slides freely along the rod 30 and can rotate with respect to it in order to contact short or long differentials. The thumbscrew 41 at the end of rod 30 permits the easy removal of the rod 30 carrying brace 14. In handling automatic transmissions and some large truck transmissions, brace 14, cradle 11 and chuck 12 are removed from base plate 10.

A convenient method of securing the base plate 10 to a hydraulic floor jack is by means of three clamps, one of which 42 may be permanent, being a simple strap welded to the bottom of the plate. The other two clamps, however, should be adjustable and, consequently, I weld to the base a pair of tracks 43 and 44 and serrate these with grooves 45 to be engaged by the sharp downturned end 46 of one of the movable clamps 47. A small boss at the end of the movable clamps 47 assists in giving a very firm connection between the hydraulic floor jack and the tool.

The rod 15 which is preferably square in cross-section, has a cylindrical end 50 which turns freely in the bracket 51 extending downwardly and outwardly from the base plate 10. In passing through the other bracket 53, however, I find it convenient to have the bearing very much larger in diameter and in this bearing I mount a disc 52 having a square hole to receive the shaft 15. This disc is held in place by washers 55 and 56. The ratchet wheel 18 has a square hole snugly receiving the rod 15 and lies between washers 56 and 57. The spool 20 may slide along the rod 15 as it has a hole snugly fitting the rod.

The cradle 11 includes two bars 60 and 61 mounted in end plates 62 and 63, the plates each being pivoted centrally on a horizontal bolt 65, the head 66 of which engages a post resting upon, but not secured to, the base plate 10. A pair of fairly large clutch plates 68 are mounted one on each side of the end plate 62 and are engaged by washers 69 and 70, the latter carrying at its bottom a horizontal bolt 72 passing through a slot 75 in the base plate and carrying an upper nut 73 by means of which and the thumb nut 74 the threaded post 72 and the horizontal bolt 65 may be elevated or lowered. The vertical post 72 also provides means whereby the cradle may be held either in its normal position parallel to one of the ends of the plates or the two vertical posts 72 may be moved to opposite ends of their respective slots 75, in which case the cradle makes a considerable angle with the edge of the plate, depending upon the length of the slot 75. I find that a slot length of about 2" is ample to take care of any work that may be expected. When the cradle is in adjusted position the vertical post is locked by the thumb nut 74 and the relative heights of the bars 60 and 61 above the plate is secured by the end thumb nuts 64. I find it quite convenient to curve one end of each end plate as at 77, while leaving the other corner 78 a right angle to engage the top of the base plate 10 firmly when the bars 60 and 61 are equally distant from the top of the base plate.

The pawl 80 for ratchet wheel 18 is pivoted as at 81 between the bracket 53 and a parallel bracket 84 welded to the base plate 10 and to lug 34. The pawl is spring pressed to active position by a spring 86 but may be held out of action by a small lever 87 pivoted as at 88 to bracket 53 and for convenient operation having an inverted fingerpiece 89 extending below and beyond the far side of bracket 53. This lever is of considerable use as it saves the need for applying a brake to the shaft 15.

Frequently it happens that a large mechanism must be removed from the automobile in one position but after it is taken out of place it is easier to handle that particular piece of mechanism if it could be turned through a considerable angle, often 90°.

By moving one of the two levers 87 out of contact with its ratchet pawl, thereby leaving the latter operative, while having the opposite lever hold its pawl out of engagement with its ratchet wheel, a large heavy piece can readily be turned over, remembering that each of the two shafts 15 are manually controlled by a simple open-ended wrench with its opening of the same size as the square rod, $\frac{7}{16}$ " for example. Consequently, a five-forward-speed transmission can be let down from its normal position in the truck and then may be rolled over by loosening one cable and tightening the other, this making it possible for one man to complete the operation in only a few minutes and without the usual need for taking off the gear shift lever. After repair, the transmission can readily be straightened up again on the base plate for replacing in the truck by having one lever holding its pawl out of position and the other lever being free of its pawl which latter then, by urge of the spring 86, engages its ratchet wheel. Any piece of mechanism may therefore be rolled over on the base plate and held at any angle desired by the operator holding one wrench on one shaft with one hand to release slowly one cable and holding a similar wrench in the other hand to operate the shaft which is tightening the other cable. The cables are preferably of multistrand wire and are quite flexible.

While I much prefer that the brace 14 be free to rotate and to slide on rod 30, I may lock the sleeve 90 of inner section 36 to the rod 30 by a set-screw such as 91 and thus fasten the brace 14 in desired angular position by tightening the thumb-screw 41.

What I claim is:

1. A garage tool comprising a rectangular base plate having a pair of slots therein, a pair of post assemblies adjustably mounted in said slots for movement up and down with respect to the base as well as along the slots, a pair of coaxial pivot pins carried by the posts, a cradle mounted on said pivot pins, means for locking the cradle at a chosen angle on the pins, means for clamping the posts in chosen position on the base, a pair of cables extending on opposite sides of the cradle and cable tensioning means fastened to opposite sides of the base plate for binding an object resting on the cradle to the base plate.

2. The tool of claim 1 in which the cable tensioning means includes at each end of the base plate, a cable winding shaft roughly normal to the axis of the cradle, a hook on the shaft for holding the free end of the cable from the opposite shaft, means for latching the shaft in adjusted positions, and means for holding the last-named means inoperative.

3. A garage tool adapted to be carried by a floor jack for use in supporting a heavy member of an automobile mechanism to be repaired, comprising a rigid base having parallel sides, a pair of shafts each having a flat side and being pivotally mounted at the opposite parallel sides of said base to be independently manually rotated about their respective axes, a spool slidable on each shaft and having an internal flat side to prevent relative rotation of the spool and shaft, a flexible cable secured to each spool to engage the mechanism on said base, and means for preventing rotation of either shaft at will, whereby the two shafts may be rotated independently of each other by a two-handed operation to apply tension to the cables to bind said mechanism to the base with the means operative, and then allowing the position of the mechanism to change with at least a portion of the means inoperative, so that a single worker may let said mechanism down from its normal position in the automobile and then let the member roll over to a desired position on the base by slowly loosening one cable while tightening the other cable.

4. The tool of claim 3 in which each cable carries at its free end a loop, the cables extend roughly parallel to each other, and an anchoring member slides on each shaft to receive the looped end of the cable carried by the spool on the opposite shaft.

5. The tool of claim 3 in which each shaft is square in cross section, and the means on each shaft includes a ratchet wheel, a pawl engaging such ratchet wheel, and a pawl engaging member to hold the pawl inoperative, whereby the worker may turn either shaft clockwise or counter-clockwise with an open-ended wrench fitting the square shaft when its pawl is held in inoperative position, and may turn the shaft in one direction only when the pawl is in normal operative position.
